UNITED STATES PATENT OFFICE.

WILLIAM I. GAHRIS, OF SEBRING, OHIO.

DESIGN FOR A PLATE OR SIMILAR ARTICLE.

49,088.

Specification for Design.

Patented May 23, 1916.

Application filed February 5, 1916. Serial No. 76,477. Term of patent 3½ years.

To all whom it may concern:

Be it known that I, WILLIAM I. GAHRIS, a citizen of the United States, residing at Sebring, in the county of Mahoning and State of Ohio, have invented a new, original, and ornamental Design for a Plate or Similar Article, of which the following is a specification, reference being had to the accompanying drawing, forming part thereof.

Copies of this patent may be obtained for five cents each, by addressing the "Commissioner of Patents, Washington, D. C."

The figure is a plan view of a plate showing my new design.

I claim:

The ornamental design for a plate or similar article, as shown.

WILLIAM I. GAHRIS.
